COOKING THERMOMETER FOR MEAT OR THE LIKE

Charles L. De Martin, Brighton, and Edwin J. Smith,
Irondequoit, N.Y., assignors to Scott Thermo-Meter
Corporation, Rochester, N.Y., a corporation of New
York

Filed Apr. 21, 1961, Ser. No. 64,843

Term of patent 3½ years

(Cl. D52—7)

FIG. 1

FIG. 2

FIG. 1 is a side elevation of a cooking thermometer for meat or the like embodying our new design; and

FIG. 2 is a bottom plan view thereof.

The portions of the side of the thermometer, which are not shown, are substantially the same in appearance as the portion shown.

We claim:

The ornamental design for a cooking thermometer or the like substantially as shown and described.
